US0D1054777S

(12) **United States Design Patent** (10) Patent No.: **US D1,054,777 S**
(45) Date of Patent: ** Dec. 24, 2024

(54) **BAKEWARE**

- (71) Applicant: **Ningbo Lisi Houseware Co., Ltd.**, Ningbo (CN)
- (72) Inventors: **Li Lixin**, Ningbo (CN); **Zheng Suwei**, Ningbo (CN)
- (73) Assignee: **Ningbo Lisi Houseware Co., Ltd.**, Ningbo (CN)
- (**) Term: **15 Years**
- (21) Appl. No.: **29/946,787**
- (22) Filed: **Jun. 11, 2024**

Related U.S. Application Data

- (63) Continuation of application No. 29/885,652, filed on Feb. 27, 2023, now Pat. No. Des. 1,037,759.

(30) **Foreign Application Priority Data**
